UNITED STATES PATENT OFFICE

2,110,325

AIRDROME

Joseph G. De Faria, Mansfield, Mass.

Application February 2, 1937, Serial No. 123,710

2 Claims. (Cl. 244—114)

This invention appertains to new and useful improvements in airdromes and more particularly to an underground airdrome.

The principal object of the present invention is to provide an airdrome built in the main underground so that aircraft can quickly and conveniently drive into the same.

Another important object of the invention is to provide an airdrome which will eliminate the hazardous presence of hangars and other auxiliary buildings at airports, by having all housed facilities located underground.

Still another important object of the invention is to provide an airdrome which will lessen the requirement for large landing fields by providing means whereby the aircraft is retarded and caught in flight and conveyed to the inside of the airdrome where the plane, passengers and shipments can get off regardless of weather conditions.

These and various other important objects and advantages of the invention will become apparent to the reader of the following specification.

In the drawings:—

Figure 1 represents a fragmentary top plan view of the airdrome.

Figure 2 is a fragmentary longitudinal sectional view taken substantially on the line 2—2 of Figure 1.

Figure 3 is a fragmentary vertical sectional view taken substantially on the line 3—3 of Figure 2.

Figure 4 is a fragmentary horizontal sectional view taken substantially on the line 4—4 of Figure 2.

Figure 5 is an enlarged fragmentary vertical sectional view taken substantially on the line 5—5 of Figure 2.

Figure 6 is a fragmentary side elevational view of the upper end of the plane catching conveyor.

Figure 7 is a top plan view of the upper portion of the plane catching conveyor, shown partly in section.

Referring to the drawings wherein like numerals designate like parts, it can be seen that numeral 5 represents the airfield, preferably of concrete reinforced construction under which are the compartments 6 forming the various quarters of the airdrome. This field 5 is provided with a circular opening 7 therein for receiving the rotary assembly 8 which is rotated by machine or convenient manual means, whereby the inlet end 9 of the elongated hood 10 can be set in accordance with the wind direction.

55 A wind tunnel 11 is provided on the inside of

the hood 10, the same having the mesh covered air inlet 12 and the grilled air outlet 13. Mounted within this tunnel 11 is the motor 14 driving the propeller 15 directing air toward the aircraft inlet 9. Numeral 16 represents the base of the rotor 8 from which rises the ramp 17 to terminate flush with the field 5 and also the ramp 18 rising from the base 16 to terminate flush with the field 5. The upper ends of these ramps 17—18 are secured to the top 19 of the rotary assembly 8 and from the peripheral portion of this top 19 roller mounts 20 depend with their rollers thereof riding in the annular trackway 21 which is supported by suitable brackets 23. Thus, the rotary assembly 8 is rotatably supported and planes can leave the field and enter the airdrome by way of the ramp 17, or leave the airdrome through the field by way of the ramp 18.

Mounted within the lower portion of the rotary assembly 8 is the sprocket wheel 24 and within the top portion of the dome entrance 9 is mounted a second sprocket wheel 25. Over these sprocket wheels 24—25 is trained the endless sprocket chain 26 which is equipped with a pair of swingable eye members 27—28 at equal distant positions on the chain, so that when an aircraft 29 equipped with the necessary hook 30 approaches the entrance 9 of the hood 10 and is slowed down by the draft of air from the propeller 15 and engages the hook 30 into the eye member 28, the weight of the aircraft will carry the same down to the base 16 of the rotary assembly 8 and while the plane is thus lowering itself to the base 16, the eye member 27 has been carried upwardly to replace the eye member 28. In this manner there is always an eye member 27 or 28 located at the entrance 9 of the hood 10. A search light 31 can be positioned in the entrance 9 for illuminating the adjacent eye member 27 or 28.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. An airdrome comprising an airfield having a depression therein, a rotary assembly mounted in the depression and having a hood-like structure rising therefrom, said hood-like structure being provided with an aircraft entrance, and means carried by the assembly for lowering an aircraft from the said entrance to the bottom of the said rotary assembly, said means for lowering

an aircraft into the rotary assembly consisting of an inclinedly disposed endless element having eye members thereon under which aircrafts can hook.

5 2. In combination, an aircraft having a hook thereon, a subterranean airdrome, an inclinedly disposed endless element having eye members

thereon and extending downwardly into the said airdrome, the hook of the aircraft being adapted for engagement with an eye of the endless element and pneumatic means for retarding the movement of the aircraft when engaged on said endless element. 5

JOSEPH G. DE FARIA.
